UNITED STATES PATENT OFFICE.

JAY E. LEHMAN, OF CANTON, OHIO.

GASOLENE-MOTOR.

1,332,265.

Specification of Letters Patent.

Patented Mar. 2, 1920.

Application filed March 19, 1918. Serial No. 223,429.

To all whom it may concern:

Be it known that I, JAY E. LEHMAN, a citizen of the United States, residing at Canton, in the county of Stark and State of 5 Ohio, have invented a new and useful Gasolene-Motor, of which the following is a specification.

This invention relates to gasolene motors of the four cycle type and more especially 10 to valve construction for the same, the object being to construct a valve designed to slidably cover and uncover the cylinder ports.

Another object is to construct a gasolene 15 motor of a sliding valve type in which both the intake and exhaust passages to each cylinder are controlled by one valve.

A further object is to construct a valve 20 on the sliding principle, thereby doing away with the valve seat necessary in the puppet type of valve thus eliminating the carbon-collecting valve seat and other objections of the puppet valve.

With these objects in view the invention 25 consists in the novel construction and arrangement of parts, hereinafter described, illustrated in the accompanying drawings, and particularly pointed out in the appended claims, it being understood that various 30 changes in the form, proportions, size and minor details of construction may be made within the scope of the appended claims, without departing from the spirit or sacrificing any of the advantages of the invention. 35

In the drawings:

Figure 1 is a cross sectional view through a gasolene motor constructed in accordance with my invention, the timing gears and 40 drive chain therefor being shown in elevation and partly broken away.

Fig. 2 is a detail plan view on a slightly enlarged scale of a pair of the valve operating cams for one cylinder, the valve push 45 rod being shown in section.

Fig. 3 is a side elevation of a pair of cams for one valve, the cam shaft being shown in section and showing a portion of the valve push rod.

50 Similar numerals of reference indicate corresponding parts throughout the several figures of the drawing.

1 indicates the cylinder, 2 the piston, 4 the connecting rod and 5 the crank shaft 55 of a gasolene motor, all of ordinary construction used in this class of engines. A

port 6 forms a passage from the interior of the cylinder 1 to the valve chamber 7. An inlet port 8 from the carburetor and an exhaust port 9 also open into the valve chamber 7. The valve chamber is cylindrical and fitting within this chamber is a cylindrical valve 10 having a reduced portion 11, the purpose of which will be hereinafter specified. A cam shaft 12 is mounted in direct alinement below the valve chamber 7 and carries a timing gear 14. A chain 15 operating over this gear is driven by a gear 16 mounted on the crank shaft, the gear 14 being provided with precisely twice the 70 number of teeth as the gear 16, thus the crank shaft 5 will make two revolutions to each revolution of the cam shaft 12.

Formed upon the cam shaft 12 is a pair of cams 17 and 18 for each cylinder of the 75 motor, these cams being positioned upon either side of the push rod 19 of the valve 10. A pin 20 secured through the lower end of the push rod 19 extends above the cams 17 and 18 as shown and carries anti-friction rollers 21 and 22, which rest upon the bifurcated ends of a pivoted arm 24, which bifurcated ends are interposed between the rollers 21 and 22 and their respective cams 17 and 18. A coil spring 25 which 80 encircles the push rod 19 is interposed between a pin 26 inserted through the push rod and the bearing 27 formed in the valve chamber and exerts a constant downward force thus holding the rollers 21 and 22 in 85 constant contact with the bifurcated portion of the arm 24 and said bifurcated portions in constant contact with the cams 17 and 18.

In the drawings the piston 2 is shown in the position which it would assume at the 95 instant the gas is ignited to cause the explosion. The valve 10 is now positioned by the cams to close the passage 6 and the ports 8 and 9. We will assume that the charge of compressed gas within the cylinder 1 is now ignited causing the explosion 100 and forcing the piston downward. When the piston reaches the limit of its downward movement on the firing stroke the crank shaft will naturally have made one-half of a 105 revolution and since the timing gear 16 has precisely half the number of teeth of the gear 14, the cam shaft 12 will have made exactly one-quarter of a revolution.

In Fig. 3 the cams are shown in the position which they would assume when the valve is in the position shown in Fig. 1, or

with the piston at the beginning of the firing stroke. The descent of the piston on the firing stroke will obviously cause the cam shaft to be rotated one-quarter of a revolution and bring the point marked "A" on the cam to position beneath the pin 20 and its rollers. The cams are concentric from the point directly beneath the pin 20 in Fig. 3 to the point A, thus the valve will remain 10 in the position shown in Fig. 1, holding all ports closed during the firing stroke. When the piston begins its upward travel on the scavenging stroke the point A on the cams immediately passes beyond the ends of the 15 bifurcations of the arm 24 and allows the said arms to be forced down under the tension of the spring 25, until it contacts with the reduced portions of the cams beginning at the point B. This obviously permits the 20 valve 10 to drop, exposing the exhaust port 9 and the passage 6 but holding the intake port 8 closed. The bifurcations of the arm 24 traveling from the point B to the point C during the quarter revolution of the crank 25 shaft during the scavenging stroke will allow the exhaust port 9 to remain open. Reaching the limit of its upward movement on the scavenging stroke the piston is now ready to descend on the suction stroke and the cams 30 have been rotated to now bring the point D into contact with the arm 24, forcing the push rod upward closing the port 9 and opening the port 8 and passage 6, the portion of the cam between the points D and E 35 holding the intake port thus opened during the suction stroke of the piston. When the piston begins its upward movement on the compression stroke the concentric portion of the cams beginning with the point E will 40 once more have come beneath the rollers 21 and 22, thus positioning the valve 10 to close all of the ports.

Having fully described my invention what I claim as new and desire to secure by 45 Letters Patent, is:

1. A gasoline motor of the class described having a valve chamber adjacent each cylinder, a sliding valve within each of said valve chambers, a push rod connected to 50 each of said valves, a cam shaft rotatably mounted in vertical alinement beneath said

push rods, a cam formed upon said cam shaft adjacent either side of the lower extremity of each push rod, a bifurcated arm pivoted in horizontal alinement with said cams, one of 55 the bifurcations of said arm lying upon each of the said cams, a roller mounted upon either side of said push rod and above said cams and said bifurcations and a spring operatively engaging said push rod to force the 60 said rollers into constant engagement with the said bifurcations and to hold the said bifurcations in constant engagement with the said cams.

2. A gasoline motor of the character 65 described having a valve chamber located adjacent each cylinder, a piston located within each of said cylinders, a sliding valve within each of said valve chambers, a communicating passage between each of said cylinders and its adjacent valve chamber, an intake port and an exhaust port entering each of said valve chambers, a push rod extending downwardly from each of said valves, a cam shaft rotatably mounted in 70 vertical alinement beneath said push rods, a pair of cams arranged upon said cam shaft adjacent the lower end of each of said push rods, rollers carried upon said push rods and above said cams, a bifurcated arm 75 pivoted adjacent said cam shaft, the said bifurcations lying upon said cams and beneath said rollers, a coil spring operatively engaging each of said push rods to hold said rollers in constant engagement with said 80 bifurcations and to hold said bifurcations in 85 constant engagement with said cams and means for rotating the said cam shaft to position the said sliding valve to simultaneously open the intake port and communicating passage and to close the exhaust port when the said piston descends on its suction 90 stroke and to simultaneously open the exhaust port and passage and close the intake port when the piston ascends on its scavenging 95 stroke and for holding both of said ports and said passage closed while the piston descends on its firing stroke and ascends on its compression stroke.

In testimony that I claim the above, I 100 have hereunto subscribed my name.

JAY E. LEHMAN.
